[57] **CLAIM**

The ornamental design for a bed mounted fan, as shown and described.

DESCRIPTION

FIG. 1 is an isometric view of a bed mounted fan, showing my new design;

FIG. 2 is a front elevation view thereof;

FIG. 3 is a rear elevation view thereof;

FIG. 4 is a top plan view thereof;

FIG. 5 is a bottom plan view thereof with the fan removed;

FIG. 6 is a right side elevation view of the fan with the housing shown in cross section; and

FIG. 7 is an isometric view of a bed mounted fan showing a second embodiment of my new design, the sole difference residing in the addition of a second fan and an increase in the width of the housing.

The electrical cord and plug are shown broken away in FIG. 3 to indicate indeterminate length and the electrical cord is broken away in FIGS. 1, 6, and 7 for convenience of illustration.
